UNITED STATES PATENT OFFICE.

OTTO J. KUENHOLD, OF CLEVELAND, OHIO.

HEATER FOR GARAGES AND OTHER USES.

1,392,016.

Specification of Letters Patent. Patented Sept. 27, 1921.

Application filed December 13, 1915, Serial No. 66,652. Renewed May 8, 1918. Serial No. 332,930.

To all whom it may concern:

Be it known that I, OTTO J. KUENHOLD, citizen of the United States, residing at Cleveland, in the county of Cuyahoga and 5 State of Ohio, have invented certain new and useful Improvements in Heaters for Garages and other Uses, of which the following is a specification.

This invention pertains to a heater for 10 garages and other uses, all substantially as shown and described and particularly pointed out in the claims.

The object of the invention primarily is 15 to provide a heater which is particularly constructed to be absolutely safe in operation and to be ignited without danger of explosion or fire in all places where ignition of explosive or inflammable mixture might be present, as in garages, gasolene cleaning 20 establishments, gas generating plants, etc.

My application Serial No. 66652, of which the present application is a renewal, was co-pending with and is therefore a continuation of my earlier application, Serial No. 25 56515, as to all subject-matter which is common to both applications.

In the accompanying drawings, Figure 1 is a front end elevation of the heater or stove shown as adapted to be supported in 30 part from a wall by brackets at its top and legs at its inner side and Fig. 2 is a side elevation of Fig. 1, partly broken away at the rear and side.

Fig. 3 is a plan view on line 3—3, Fig. 4, 35 and Fig. 4 is a vertical central sectional elevation lengthwise of the lower portion of the heater.

Fig. 5 is a perspective inside view of the main or supporting front plate, and Fig. 40 6 is a side elevation of one of the side plates. Fig. 7 is a perspective view of the end plate of the burner chamber, and Fig. 8 is a plan view of the burner.

Fig. 9 is a cross section substantially on 45 line 9—9, Fig. 2. Fig. 10 is a cross section of an auxiliary plate shown in Fig. 11 on section line 10—10 thereon. Fig. 11 is a front view of the said plate and which carries the ignition and other parts, and Fig. 50 12 is a vertical section thereof. Fig. 13 is a detail of a window plate at the front of the stove, and Fig. 14 is a perspective view of another window plate as hereinafter described. Fig. 15 is a perspective view of 55 a brush adapted to cleanse the perforated

or gauze plates at the bottom of the heater or stove. Fig. 16 is a perspective view of the lock plate.

The heater as thus shown is designed for use more especially in garages and other places where hydro-carbon vapors are liable to be found in dangerous volume, and the construction is such that ignition of such vapors through the use of the heater is impossible. The burner of the heater is 60 enclosed in such manner that its flame cannot ignite gases or vapors outside of the enclosure, and provision is made for preventing opening of the heater while the burner is in operation, either to light the burner or 65 for any other purpose, a mechanical igniting device located within the heater, but operable from without, being provided so as to make opening of the heater unnecessary. Air for the propagation and support 70 of combustion is taken from the apartment in which the heater is located, thereby providing warm instead of cold air for the purpose, and at the same time avoiding the danger of the flame being extinguished or 75 disturbed by wind or an excessive draft.

In the accompanying drawings, Figure 1 is a front end elevation of the heater or stove shown as adapted to be supported in 80 part from a wall by brackets at its top and legs at its inner side and Fig. 2 is a side elevation of Fig. 1, partly broken away at the rear and side. This also simplifies the work of installing the heater. A flue is provided, designed to produce just 85 the proper draft for the most effective operation of the heater; this flue is arranged to discharge the products of combustion into the apartment containing the heater. If desired, however, the products of combustion may be conducted by a super-flue to 90 a chimney or other outlet, and provision is made for preventing any disturbance of the draft under which the heater is designed to operate, by conditions obtaining in or produced by the super-flue.

To these several ends and others the stove is built up with a number of plates and parts which constitute, first, an outer 95 enclosure, casing or wall, an inner heat radiating inclosure or drum and a combustion chamber within the front thereof and a draft flue F open to the bottom of said radiating chamber to carry off the products of combustion.

The outer casing comprises a cast iron front plate P, shown in perspective in Fig. 5, upon which all of the other front parts are assembled. The sides 2 of this outer casing are of sheet metal, suitably secured 100

105

110

to the front plate P and the back plate P'. The bottom of the casing is open and the top is covered by a coarse wire mesh. The bottom of the combustion chamber is composed 5 of two finely perforated V-shaped plates 3 and 4 set apart so as to leave a space between them. The air which enters the combustion chamber is required to pass through these plates. The rear portion of plate 3, 10 designated by the numeral 11 in Fig. 4, is not perforated.

The said main or supporting front plate P is provided with various flanges upon its inside with which to make sealed connection 15 of the parts supported thereon as will now appear. Thus, the said bottom plates 3 and 4 are seated snugly at their ends in the V-shaped channels on opposite sides of the rib or wall 5, and said plates are united by a 20 lock seam with the drum bottom which extends to the rear plate P'.

The prime object of introducing air to the heater through a perforated screen is to prevent ignition by the burner of any gases 25 or vapors which may surround the heater. It is well known that finely perforated metal, or wire gauze, will resist the passage of flame and that inflammable gas on one side of such a screen will not be ignited by 30 a flame on the other side of the gauze. A single screen is sufficient for this purpose, provided the perforations are fine enough, and in my former application, Serial No. 56,515, I showed a heater having but a single screen. My object in using a double 35 screen is that larger perforations may be used, affording a freer entrance for air and simplifying the problem of keeping the screen clean. The principle on which the 40 screen acts to prevent ignition of gases outside of the heater is this:

Various ignitable mixtures of gas or vapor and air have different ignition temperatures. Combustion will not start until the ignition 45 temperature is reached and ceases if the temperature of the flame is reduced below the ignition temperature. A perforated screen is enabled to resist the passage of flame because of its ability to cool the ignited gas to a point below its ignition temperature and thus extinguish the flame. An inflammable gas may be passed through a 50 perforated screen and ignited on the opposite side of the screen. The flame will burn 55 close to the screen but not actually touch it, because in the immediate vicinity of the screen the heat is conducted away from the flame through the screen so fast that a temperature high enough to permit combustion 60 to continue cannot exist. It follows, therefore, that the most effective screen is one capable of conducting away the most heat. A copper screen is more effective than an 65 iron one; dull finished copper would be more effective than polished. In case of a

quantity of gas becoming ignited in the heater; in other words, in case of an internal explosion, the flame may be hurled against the screen with such speed as to be forced through the screen openings before it can be cooled to extinction by the screen. It is possible to make the openings small enough and the screen thick enough to prevent this, but there are practical objections to such a screen, so I prefer to make the screen double, 70 with an air space between. While the first screen may not quite stop the flame it will retard and to some extent cool it, so that the outer screen is certain to stop it.

The V-shaped screen affords a greater area 75 for intake of air, proportional to the width of the chamber, and where moisture is present and condensation occurs in the heater the condensation will gravitate to the lower portion and not close the perforations by capillary action as is likely to occur in a flat horizontal screen. In order to dispose of condensation I provide a drain d', this in the present construction being a short tube 80 screwed into the rear plate P' at the lowest part of the drum. This tube is small in diameter relative to its length, so as to preclude the possibility of flame passing through it in the event of an explosion of gas in the drum. Scale and rust will also gravitate to 85 the bottom of the V.

Lining plates 7 are provided at each side 90 of the combustion chamber, and right angled ears e or lugs are used at the front bottom corners of said plates to seat in recesses r in the inner flange 8 of the front plate P, while the front edges of the inner sheet metal walls of the inner drum d are tightly seated in the channeled wall by said flanges 8 and an adjacent flange 8'. The rear ends 95 of said side lining plates have parallel ribs 100 13 forming grooves adapted to receive the edges of the rear plate 12 of the combustion chamber, said plate having shoulders 10 on which the lower edges of the side linings 105 rest. The bottom of the plate 12 is V-shaped and sits down in the unperforated portion 110 of the plate 3.

The burner B is preferably a hollow perforated body having lateral projections 14 115 at its respective corners adapted to rest upon the lugs or ledges e and 9 on the side lining plates 7. The inner ribs 13 on said plates are shorter than the outer ones and at their lower ends turn inward a short distance, 120 these in-turned portions being above the ledges 9 a distance about equal to the vertical width of the rear projections 14 on the burner, and serving to prevent the rear end of the burner from lifting up. Gas is supplied to said burner by the pipe connection 17 and the jet 18 discharging into the mixing tube 19 fixed to the burner. The jet 18 enters through a flanged mixer tube 20, 125 which is closely packed about the same be- 130

tween the two plates D and E, and the flange on said collar bears against lock plate E in front of said packing and confines same in place. Cover plate D is fashioned to rest 5 against the front plate P with a practically sealed closure, and it is featured as seen particularly in Figs. 10, 11 and 12. Among the said features is a hole h opposite the end of burner B adapted to receive a screw stud 10 bolt 21 screwed into the burner and serving to lock the said parts together against or upon the intervening front plate P through the flat-faced angular lugs e on the side plates 7, Fig. 4. The nut on said bolt 21 is 15 purposely blinded or concealed within a cavity or cap 22 on the lock plate E so that the said bolt cannot be removed without dismantling the gas connections. This is in the interest of safety against accidental explosions as above described; in other words it is impossible to open the heater while a flame is burning inside.

Now, following the features of the said cover plate D, it is especially to be noticed, 20 that it supports an initial lighting or pilot jet 24, which has a gas supply connection 25 with the pipe 17 beneath and a specially provided ignition device in the angle seen in Fig. 10 and comprising a rotatable 25 sharply milled wheel 27 having a stem and handle 28 to rotate the same and adapted to engage the end of a pyrophoric metal pin or piece 29 held in contact therewith by a 30 backing spring 29'. In this way a shower 35 of sparks may be projected upward to ignite said initial jet or burner. This arrangement is especially desirable for present use because the spark is confined to the inside of the front of the stove or heater and 40 not exposed outside. The pyrophoric member 29 and spring 29' is held in place by a pressure adjusting screw 28', and ignition occurs at the jet 24 which ignites the gas at the burner B. The milled wheel 29 and 45 its operating stem 28 is placed at an angle, preferably at right angles, to the pyrophoric member 29 and its adjusting screw 28', so that both operating parts may be reached and manipulated from the outside, and the 50 pyrophoric member replaced when needed. In brief, cover plate D requires no removal to operate or replace the parts.

Fig. 15 shows a brush 33 of substantially V-shape with bristles at both edges and 55 adapted to be used in the correspondingly shaped space between the two perforated plates or screens 3 and 4, Fig. 4, when the perforations become fouled, as will unavoidably occur from dust drawn in from the outside. This brush may be operated by a stem or handle 33' extending through the front 60 plate.

Figs. 13 and 14 show two holding frames 65 30 and 31, which are secured on opposite sides of the cover plate D by two bolts or screws

and nuts which are confined within square recess 31' in frame 31. Being in square recesses the nuts cannot be turned; therefore the frame 31 cannot be removed without first removing the plate D, this being 70 impossible without first breaking the fuel connection, as will presently be more fully explained. The frame 30 with its glass window 32 is on the inside of said plate and the frame 31 with its mica window on 75 the outside thereof. In this way a double window is provided as a precaution against opening the stove and thereby possibly igniting outside gases from a flame within the heater. The air space between the glass 80 and mica serves a very useful purpose in that it keeps the mica comparatively cool, so that it will not laminate as mica eventually does in the presence of great heat. Glass, on the other hand, is capable of withstanding intense heat provided it is surrounded by air and is not subjected to sudden chilling. The mica therefore protects the glass from being broken by water, which is liable to be splashed upon it in a garage, or 85 by cold drafts that might strike it when the garage door is opened, while the glass protects the mica and preserves its transparency. The inner frame projects downward to shield the ignition mechanism 90 comprising wheel 27 and member 29 from the intense heat, but an opening 30' is provided in this frame opposite the pilot light for the pilot flame, and a vertical passage or space 34 is also left open between plate 95 30 and plate D for an upward draft of air to supply the pilot light and to keep the parts as cool as possible and avoid drawing of the temper out of the ignition mechanism. By this arrangement the ignition mechanism 100 is isolated from the main burner, which it could not well be if it were required to light the burner directly. After the burner is lighted the pilot flame may be extinguished, cutting off certain expense and eliminating 105 heat from the immediate vicinity of the ignition device.

Further precaution is accomplished by the arrangement and connection of the several parts at the front of the heater and in which 110 the single bolt 21 is the key. Thus, it has been seen that the parts constituting the combustion chamber are interlocked with each other and the burner B, and they are drawn against the main front plate P and 115 locked therewith exclusively by said bolt 21. Remove this bolt and said parts may be dis-assembled. In front of this arrangement is the lock plate E, which covers bolt 21 and prevents possible tampering therewith by wrench or the like, and said plate E is confined by the flange on sleeve 20 as described. Mixer tube 20 is rotatable to 120 control the air passing to the burner, but is in turn confined by the valve body and 125 130

gas supply pipes which are secured to the stove by the bracket b' and the screw extension of pilot valve 24, and hence accessibility to the bolt 21 is possible only by first 5 removing the fixed gas pipe connections, the tube 20 and the cover plate E. This of course means cutting off the gas supply and the dismantling of the heater. The lock plate E has a squared recess 22 to hold the 10 nut 36 of the screw stud from turning. The nut 36 may be a separate or an integral part of the stud 21.

Confining the rear plate 12 between the parallel ribs 13 on the side linings forms a 15 sort of slip joint by which the three plates are connected and permits outward movement of the side walls, with consequent enlargement of the combustion chamber, without opening the joints and permitting 20 products of combustion to pass directly from the combustion chamber to the flue. The side walls of the drum bear against the side lining plates and hold them in position. No bolts or screws are used through 25 the drums or the lining plates, nor are they needed with this arrangement, and the reason for so constructing the heater is to avoid leakage of gas through the drum and to permit ready expansion and 30 lateral separation of the walls and parts without disrupting the heater during initial ignition of accumulated gases within the combustion chamber. The drum walls are 35 of sheet metal and possess sufficient spring qualities to yield and to hold the parts together. The top of the drum is V-shaped as well as the bottom, for two reasons. First, it prevents an accumulation of dust on the top, which would reduce radiation of heat 40 therefrom, and, second, it facilitates expansion of the drum in case of an interior explosion. The side walls having a large flat area, are enabled, because of their attachment to the V-shaped sections at the top 45 and bottom, to bulge outward a considerable distance, thus greatly increasing the capacity of the drum, momentarily, without any permanent distortion of the parts.

As has been previously stated the products 50 of combustion are carried off by a flue F. This flue terminates, preferably, at about the plane of the top of the outer casing of the heater, and takes the products of combustion from the bottom of the radiating 55 compartment, thus compelling said products of combustion to traverse a long, circuitous path before reaching the flue. The cross sectional area of the flue is made such with reference to its length that the draft through 60 the heater shall be rather slow, so as to require the products of combustion to pass lazily through the heater, giving up practically all of the heat contained therein. The capacity of the perforated plates 3 and 65 4 for admitting air is also gaged with this

in view. In Fig. 2 the flue is surmounted by a draft equalizing device which may be connected by a pipe to a chimney or other means for carrying the products of combustion from the building. This super-flue, 70 and therefore the draft equalizer, are not necessary, however, to the safety of the heater, as the flue is so remote from the burner as practically to preclude the possibility of flame issuing from the upper end. 75 But many persons object to the products of combustion entering the room, and in providing for conducting them from the room I include the draft equalizer, so that whatever the new conditions may be the draft 80 through the heater shall not be materially affected. The draft equalizer comprises a cap f fitted to the flue F, said cap having lateral openings f'. Surrounding this cap is a hood f², open at the bottom and supported 85 at the top by a short piece of pipe, f³, which is in turn supported by the cap f. Openings f⁴ in the pipe f³ allow products of combustion which have issued from openings f' to enter pipe f³. The pipe f³ may be connected to a chimney or some other super-flue and the products of combustion thereby conducted from the building. By means of the damper f⁵ the outlet through pipe f³ may be 90 cut off, the products of combustion then being compelled to enter the room. With this arrangement the draft in the flue F is practically unaffected by the draft in the super-flue, the large opening at the bottom of the hood admitting air from the room so freely 100 as not to permit the super-flue to draw from the flue F. Moreover, the cap f prevents down drafts from affecting the operation 95 of the heater.

The flue is secured to the heater by being 105 fitted snugly in a hole at the bottom of plate P' a collar p' protruding outward from the plate, against which the throat of the elbow f⁶ impinges. The end of the elbow is flanged over on the inside of plate P' as at 110 f⁷, Fig. 2, so that it cannot be removed. It will be seen therefore that the heater is sealed at all points and that entrance thereto cannot be effected without first disconnecting the gas service, or actually breaking 115 some part of the heater.

What I claim is:

1. A heater having a combustion chamber which is sealed and locked to prevent ingress thereto and having an air intake, a flame-passage resisting screen and entrance guard for said air intake, a burner for said chamber, an ignition device for said burner sealed and locked within said chamber, and means to operate said ignition device externally of said chamber. 120

2. A heater having a fuel burner therein and fuel connection for said burner extending outside of said heater, and means to prevent access to the interior of said heater 130

- dependent upon the separating of said fuel connections.
3. A heater having a burner therein and an air entrance leading thereto having a converging screen bottom, in combination with means within said heater to clean said converging bottom.
4. A heater having a burner therein and an air entrance beneath the same provided with a double screen of V-shape in spaced relations, and a cleaning brush in the space between said screens.
5. In a heater of the character described, comprising a main front plate and an auxiliary plate thereon, a burner and walled chamber therefor, and a single bolt locking said parts together.
6. In a heater of the character described, comprising a combustion chamber and a burner supported on the walls thereof, a main front plate and an auxiliary plate thereon and a single bolt engaged through said auxiliary plate with said burner and adapted to clamp said combustion chamber to said plates.
7. In a heater of the character described, comprising a burner and a combustion chamber having side and end walls interlocked therewith, a main front plate having channels on its inside for said side plates, a plate on the outside of said main plate and a bolt through the same engaged in the end of said burner and adapted to clamp the said parts together.
8. In a heater of the character described, a combustion chamber and a burner seated on the sides thereof and fuel connections therewith, a plate at the front of said chamber, a single bolt clamping said plate and burner together and a cap fixed over the head of said bolt to prevent access thereto and means confining said cap dependent for removal on the previous removal of the fuel connections.
9. A heater having a combustion chamber, a heat radiating compartment into which the products of combustion pass, an opening in the combustion chamber covered with a foraminous screen through which air for the propagation and support of combustion is admitted, said screen being so constructed as to resist the passage of flame therethrough, and an unscreened vent flue through which the products of combustion may escape into the apartment containing the heater, the combustion chamber, radiating compartment and vent flue combined forming a passage of such length that the products of combustion will be cooled to a temperature below the temperature of ignition of any gases which may surround the heater, before said products issue from the vent flue.
10. A safety heater comprising a combustion chamber containing a gas burner, a pilot burner adapted to light the aforesaid main burner, a shield between the burners having a small hole through which the flame from the pilot burner passes to ignite the main burner, an opening for admitting fresh air to the chamber to propagate and support combustion, means whereby a portion of said fresh air may pass behind the shield, an igniting device behind said shield where it is protected from the heat of the main burner and in the current of air that passes behind the shield, said device being adapted to light the pilot burner, and means for operating the igniting device from outside the heater.
11. In a safety heater, a flame tight drum which in plan has the form of a long, narrow, right angled parallelogram, the top of the drum being an inverted V shape and its sides flat, the sides being attached to other members at their four edges only, said flat sides and V shaped top coöperating to permit a substantial enlargement of the drum in case of an internal explosion, thereby nullifying the effect of the explosion by a yielding resistance; a gas burner in one end of said drum, an opening in the bottom of the drum below said burner, covered with a foraminous shield which will admit air to the burner but resist the passage of flame, a vent in the end wall of the drum remote from the burner and near the bottom of the drum, and a bridge wall intermediate the ends of the drum, over which products of combustion are compelled to pass to reach the vent.
12. In a safety heater, an inclosed combustion chamber, a gas burner therein, and a window through which the flame of the burner may be observed, said window containing two transparent members, the inner one being composed of glass and therefore capable of standing great heat without its transparency becoming impaired, the outer member being of mica, said members being separated by an air space.
13. In a heater, the combination with a combustion chamber having an opening covered with a foraminous screen through which the air for the propagation and support of combustion is received from the apartment containing the heater, a radiating compartment and a flue; of a draft equalizer also in said apartment, comprising a cap covering the top of the flue, said cap having lateral openings for the outlet of products of combustion, and a hood surrounding the cap, said hood being adapted to connect to a chimney or other outlet whereby products of combustion discharged from said openings may be carried from the apartment containing the heater, the bottom of the hood being open and adapted to admit air freely from the apartment, thereby eliminating substantially all possibility of the draft in the chimney affecting the draft in the flue.

heater flue, the combustion chamber, radiating compartment and flue combining to form a passage for the products of combustion of such length that the products of combustion will be cooled to a temperature below the temperature of ignition of any gases which may surround the heater, before said products of combustion issue from the flue.

14. In a heater, the combination with a combustion chamber, a radiating compartment and flue, of a draft equalizer in the apartment containing the heater comprising a cap covering the top of the flue, said cap having lateral openings for the outlet of products of combustion, a hood surrounding the cap, said hood being adapted to connect to a chimney or other outlet whereby products of combustion discharged from said openings may be carried from the apartment containing the heater, the bottom of the hood being open and adapted to admit air freely from the apartment, thereby eliminating substantially all possibility of the draft in the chimney affecting the draft in the heater flue, and a damper whereby the hood may be cut off from the chimney, thereby forcing the products of combustion into the apartment, the combustion chamber, radiating compartment and flue combining to form a passage for the products of combustion of such length that the products of combustion will be cooled to a temperature below the temperature of ignition of any gases which may surround the heater, before said products of combustion issue from the flue.

15. In a safety heater, a closed drum which in plan forms a long, narrow rectangle; said drum having a V shaped bottom, which with the flat sides gives to the drum the facility for considerable increase in capacity under the strain of an internal explosion, the bottom and sides being composed of thin flexible material; and a combustion chamber in one end of said drum, comprising two rigid plates lying loosely against said flexible walls, and a bridge wall united to said plates by slip joints which permit the plates to move to and fro with the flexible walls while maintaining an effective union with the bridge wall, the lower end of the bridge wall being V shaped and resting on the V shaped bottom, the portion of the bottom within the combustion chamber being foraminous and adapted to admit air to the chamber for the support of combus-

tion, but capable of resisting the passage of flame therethrough.

16. A heater comprising a sealed drum, a burner therein and a window through which the burner may be observed; said window comprising a frame by which the transparent member is held in place, said frame being secured to the drum by bolts which pass through the frame and the drum wall, the heads of the bolts being within the drum and the nuts in square recesses in the frame, thereby preventing the removal of the frame without first gaining access to the interior of the drum.

17. A heater of the character described, comprising a gas burner confined in an inclosure to which air is admitted for the propagation and support of combustion, but from which a flame cannot escape into the room containing the heater, said burner having a mixing tube with an inlet to receive air from said inclosure; a movable element whereby the area of said inlet may be varied, a member connected to said element and passing through the wall of the inclosure to the outside thereof, whereby said element may be moved from without the inclosure and the area of the inlet varied; and means whereby opening of the inclosure so that a flame could escape therefrom is prevented until after the supply of gas to the burner has been cut off.

18. A heater of the character described, comprising a gas burner confined in an inclosure to which air is admitted for the propagation and support of combustion, but from which a flame cannot escape into the room containing the heater, said burner having a mixing tube with an inlet to receive air from said inclosure; a movable element whereby the area of said inlet may be varied, a member connected to said element and passing through the wall of the inclosure to the outside thereof, whereby said element may be moved from without the inclosure and the area of the inlet varied; a pilot within the inclosure and means for lighting the pilot from the exterior of the heater without effecting an opening in the inclosure through which a flame might escape.

In testimony whereof I affix my signature in presence of two witnesses.

OTTO J. KUENHOLD.
